UNITED STATES PATENT OFFICE

135,702

DESIGN FOR AN AIRPLANE

Francis Stephen Hornak, Bridgeport, Conn.

Application November 27, 1942, Serial No. 108,888

Term of patent 14 years

To all whom it may concern:

Be it known that I, Francis Stephen Hornak, a citizen of the United States, residing at Bridgeport, in the county of Fairfield and State of Connecticut, have invented a new, original, and ornamental Design for an Airplane, of which the following is a specification, reference being had to the accompanying drawing, forming a part thereof.

Figure 1 is a top plan view of an airplane showing my new design.

Figure 2 is a side elevational view, and

Figure 3 is a front elevational view thereof.

I claim:

The ornamental design for an airplane, as shown.

FRANCIS STEPHEN HORNAK.
